[57] CLAIM

The ornamental design for an electronic intercommunications unit, as shown and described.

DESCRIPTION

FIG. 1 is a top plan view of an electronic intercommunications unit showing our new design;

FIG. 2 is a right side elevational view thereof;

FIG. 3 is a front elevational view thereof;

FIG. 4 is a rear elevational view thereof;

FIG. 5 is a left side elevational view thereof;

FIG. 6 is a bottom plan view thereof;

FIGS. 7, 8, and 9 are vertical sectional views, taken generally along the lines 7—7, 8—8 and 9—9, respectively, in FIG. 1; and

FIG. 10 is a front and right side view from above showing in perspective, as appropriate, the design depicted in FIGS. 1, 2, and 3.
